E. BENOIST

FIGURE TOY

Filed Jan. 31, 1922

Inventor:
By Eddie Benoist.
Frank J. Hanson.
ATTORNEY.

UNITED STATES PATENT OFFICE.

EDDIE BENOIST, OF ST. LOUIS, MISSOURI.

FIGURE TOY.

Application filed January 31, 1922. Serial No. 533,090.

To all whom it may concern:

Be it known that I, EDDIE BENOIST, a citizen of the United States, residing in the city of St. Louis and State of Missouri, have 5 invented certain new and useful Improvements in Figure Toys, of which the following is a specification.

My invention relates to a simple, inexpensive and attractive toy, and is embodied in 10 a toy in which the head of any suitable figure is adapted to be revolved or rotated first in one direction and then in the other direction by periodically pulling upon a string, or cord.

15 The above and other incidental objects of the invention, which will be hereinafter more fully set forth, are accomplished by such means as are illustrated in the accompanying drawings, described in the following specification and then more particularly pointed out in the claim hereto appended.

Referring to the accompanying drawings forming a part of this specification, wherein like characters of reference denote similar 20 parts throughout the several views:

Fig. 1, is a side elevation of a toy embodying my invention.

Fig. 2, is a front elevation thereof.

Fig. 3, is a longitudinal sectional view of 25 the toy.

In carrying out the aim of my present invention, I employ a suitable figure structure comprising a body portion 1 including the legs 2 for supporting the toy in a standing position. The upper end of the body section 1 is provided with a socket 3 for receiving the downwardly extension 4 of a shoulder section 5 which shoulder section terminates in an upwardly directed neck section 6. The shoulder section 5 is provided 35 with a bore 7 which is reduced in diameter at the neck section 6, as at 8. The body section 1 is also provided with a bore 9 of a diameter the same as the bore 8 of the neck section 6.

40 Receivable, or journaled in the bores 8 and 9, is a pivot pin 10 which also passes through the bore 7 of the shoulder section 5.

Suitably fixed to the upper end of the 45 pivot pin 10, is a preferably spherical head 11. The head 11 has each half provided with the eyes 12, the nose 13 and the mouth 14 which are painted upon the head 11, as is manifest. 15 indicates hair which is also 50 painted upon the head and extending down

on opposite sides of the head to complete the facial expression of the toy.

16 indicates a pull cord, or string which passes through an opening 17 which communicates with the bore 7. The inner end 60 of the pull cord 16 is suitably fixed to the pivot pin 10 and the outer end of the cord is preferably provided with a suitable button 18.

To rotate the head of the toy in opposite 65 directions, the cord is first wound about the pivot pin 10 by turning the head in one direction by means of the fingers of the operator. After the cord 16 has been wound about the pivot pin 10, the operator merely 70 gives a quick pull upon the outer free end of the cord 16 which unwinds the cord causing the pivot pin 10, including the head 11 to rotate in one direction and the momentum of the revolving head will rewind the 75 string 16, after which the operator pulls the string again and the head 11 will then be revolved in the opposite direction, as is manifest.

19 indicates a pair of suitable arms which 80 are pivotally connected to the shoulder section 5 by means of the pivot pins 20.

21 indicates a suitable dunce cap mounted upon the head 11. A suitable bell 22 is loosely carried therein to jingle when the 85 head is revolved in opposite directions.

By rapid repeating the pulling of string 16 will cause the head to revolve first in one direction and then in the opposite direction, as the cord rewinds itself upon the pivot pin, 90 if the cord is slackened after the quick jerk or pull of the string in starting the head to revolve.

From the foregoing description, it will be apparent that I have provided a relatively 95 simple, but attractive toy, in which the head of any kind of a figure may be continuously revolved in one direction and then in the other by merely pulling quickly upon a string and permitting the string to quickly 100 slacken at the end of the pulling stroke of string.

In operating the toy, the toy may be held in one hand and operated by means of the other hand, or the toy may be held upon a 105 table, or the like.

In reduction to practice, it has been found that the particular form of this invention illustrated in the drawings and referred to in the specification as the preferred embodiment.

ment, is possibly the most efficient and practical, yet realizing that the conditions concurrent with adoption of this device will necessarily vary, it is desirable to emphasize 5 the fact that various minor changes in the design, or shape and in the details of construction, proportions and arrangement of parts may be resorted to, when required, without sacrificing any of the advantages of 10 the invention, as defined in the appended claim.

What I claim is:

A sounding figure toy comprising a body section including integral supporting legs, 15 said body having a socket formed in its upper end, a tubular shoulder section having a downwardly directed extension receivable in the socket of the body section for supporting the shoulder section in position, arms 20 pivotally connected to the shoulder section,

a neck section terminating upwardly from the shoulder section and provided with a laterally directed opening, a pivot pin revolvably supported by the body and neck sections, a spherically shaped head fixed to the 25 upper end of the pivot pin to revolve therewith, a hollow cap fixed to the head, a sounding device loosely mounted upon the head within the cap, a pull cord fixed at one end to the pivot pin and capable of being 30 wound thereupon and the free end thereof passing through the opening of the neck section, said cord when periodically pulled and quickly slackened causes the head to revolve first in one direction and then in the opposite 35 direction.

In testimony whereof, I have hereunto signed my name to the specification.

EDDIE BENOIST.
